FISH SCALER

George Radanovich, Jr., 902 E. Bowman,
South Bend 14, Ind.

Filed Oct. 18, 1961, Ser. No. 67,149

Term of patent 14 years

(Cl. D31—4)

FIG. 1

FIG. 2

FIG. 3

FIG. 4

FIGURE 1 is a bottom view of a fish scaler, showing my new design;

FIGURE 2 is a side elevational view thereof;

FIGURE 3 is an end elevational view thereof taken from the top of FIGURE 1; and

FIGURE 4 is an end elevational view thereof taken from the bottom of FIGURE 1.

The top not shown is substantially plain.

I claim:

The ornamental design for a fish scaler, substantially as shown and described.
